UNITED STATES PATENT OFFICE.

CESARE FRANCO, OF NEW YORK, N. Y.

ROTARY STEAM-ENGINE.

1,080,105

Specification of Letters Patent.

Patented Dec. 2, 1913.

Application filed July 5, 1911. Serial No. 637,043.

To all whom it may concern:

Be it known that I, CESARE FRANCO, a subject of the King of Italy, residing at New York, in the county of New York and State 5 of New York, have invented new and useful Improvements in Rotary Steam-Engines, of which the following is a specification.

This invention relates to improvements in 10 rotary engines and its object is to admit of effecting in a simple, expeditious and easy manner, the reversing of the engine.

Other objects will appear and be better understood from that embodiment of my 15 invention of which the following is a specification, reference being had to the accompanying drawings forming a part hereof in which:

Figure 1 is a plan view of the engine. 20 Fig. 2 is a side elevation. Fig. 3 is a horizontal section.

The engine consists of a cylinder B, the heads of which have eccentrically disposed bearings for the shaft H—I. The rotor consists of a block portion M fast on the shaft 25 H—I, a circular portion G and opposed pistons Z and V. The pistons Z and V have steam portions slidingly fitted in recesses P in the block M, and their outer end 30 portions extend through openings in the part G. Helical compression springs S bearing on the opposite ends of yokes e, operate to project the outer ends of the pistons into contact with the wall of the cylinder, as shown in Fig. 3.

The valve chest v has on one side a flange b which is bolted to the cylinder B, and on its opposite side has a flange w which is bolted to the main steam pipe. The passages l and n in the valve chest communicate respectively, with the exhaust passage f and steam passage g and these in turn communicate with the interior of the cylinder through the ports h and i, respectively.

45 The valve T slides in the valve chest v and operates to control the admission of steam from the steam inlet o to the steam passage g and to effect communication between the exhaust passage l and the outlet 50 m which communicates with the exhaust pipe d. Thus when the parts are arranged as shown in Fig. 3 and the valve T moved upwardly so as to clear the passage n, the steam will pass from the inlet o through the 55 passages n and g and into the cylinder through the port i. Here it will act on the

piston Z until the latter turns beyond the port h, whereupon the steam will pass outwardly through the passages f and l and when the valve is raised so as to place the 60 chamber therein in communication with the passage l, the steam moving into this chamber will seek outlet through the outlet m and exhaust pipe d.

The movement of the valve is controlled by the eccentric L at one side of the engine, and through a drive rod O movement is given to the crank arm T on the shaft Q, and by means of the arm a link R is actuated which rocks the lever q to reciprocate 70 the valve rod z and shift the valve so as to permit the entrance of the steam or its exhaust.

The fulcrum of the lever q is located at the end of an arm t which may be raised or 75 lowered by means of the lever u and locked in a segment at the outer end of the lever u so that the movement may be in the direction of the arrow A or reversed in the direction of the arrow R.

As illustrated in Fig. 3, the position of the valve is neutral, but when steam is admitted through the passage n, the shaft is rotated in the direction of arrow R, the exhaust taking place through the ports f and l, 80 but when the lever u is thrown into the position indicated in Fig. 3 by A, steam is admitted through the ports f and l to drive the eccentric to the left, the steam exhausting through the port i. It will thus be seen 85 that by changing the position of the fulcrum through the lever u, the engine may be driven in one direction or the other.

The engine is mounted on substantial standards D and e, while the shaft Q is 90 journaled in the bearings U to provide a substantial and operative device easily reversed and operated by means of steam or explosive vapor, as desired.

It is obvious that the parts may be otherwise arranged or controlled without departing from the essential features above described.

What is claimed as new is:

1. In a rotary steam engine embodying a suitable cylinder, a steam chest, a rotor eccentrically mounted upon a suitable shaft, said shaft being journaled in suitable bearings provided in the walls of the cylinder, the combination of two oppositely disposed 105 spring controlled pistons reciprocally held in the rotor and adapted for engaging the

peripheral wall of the cylinder and rotating the rotor and shaft of the engine with an eccentrically controlled valve disposed in a suitable valve seat in the steam chest, adapted for alternately opening and closing the induction port and the exhaust port of the engine whereby the steam is controlled as required to operate the engine, said valve being reciprocally seated in the valve chest 10 and having a rod projected beyond the casting thereof, said rod being pivotally secured to a lever adapted for reciprocating said valve, said lever having one end pivotally secured by link connection with a crank 15 shaft, said crank shaft being reciprocally connected with a rod which is eccentrically connected with the main driving shaft of the engine, the other end of said lever being connected by link connection with the arm 20 of an adjusting lever, whereby the fulcrum of the said lever may be shifted as required to change the position of the valve whereby the engine may be reversed.

2. In a rotary engine having suitable supporting frame, casing, cylinder, steam chest, rotor and spring actuated reciprocating pistons reciprocally held in said rotor, said rotor being mounted upon a suitable drive shaft eccentrically held in suitable journals 30 provided in the casing of the engine, the combination of a reciprocating valve disposed within the steam chest, adapted for regulating the flow of steam in the engine with means for controlling the valve comprising eccentrically actuated mechanism 35 connected with the drive shaft of the engine and the valve rod of said valve, said mechanism embodying a lever pivotally connected at its central portion to the valve rod and

having one end connected by a link with a crank arm actuated by the eccentric mechanism of the drive shaft, said lever having its opposite end pivotally connected by a link with a crank arm of a hand lever adjustably mounted upon the frame of the engine whereby the fulcrum of said lever may be changed as required to change the position of the valve whereby the engine may be reversed, substantially as and for the purposes set forth. 50

3. In a rotary steam engine, having a suitable frame, casing, cylinder, rotor, pistons, inlet and exhaust ports, a steam chest and reciprocable valve, the combination of a reversing mechanism embodying an eccentrically actuated arm supported upon the drive shaft of the engine, said arm being pivotally connected with a crank arm suitably mounted upon a rocking shaft, said shaft being journaled in suitable bearings provided 60 upon said frame, a link connecting the end of the crank arm with one end of a lever, said lever having its central portion pivotally connected with a rod provided upon the valve and adapted for actuating the valve, 65 said lever being fulcrumed at its opposite end by link connections with the arm of an adjustable hand lever, suitably mounted upon the frame of the engine whereby the position of the valve may be changed as required to reverse the engine substantially as shown and described. 70
